UNITED STATES PATENT OFFICE.

IRVING R. ALLEN, OF CHICAGO, ILLINOIS.

WARDROBE TRUNK.

Application filed May 15, 1926. Serial No. 109,253.

This invention relates to wardrobe trunks, and more particularly to that type of wardrobe trunk known as an "open top" trunk, which, as is well understood, comprises a wardrobe trunk of which the garment section is open at the top, and covered by a lid or cover hinged to the garment section or by a lid or cover hinged to the drawer section, and arranged to close the open top of the garment section. The principal object of the present invention is to provide a movable pad or cushion of novel form and arrangement, for preventing the shifting during transportation, of the garment hangers and garments supported thereby, and for preventing pilfering or theft of the garments when the trunk is left open.

Wardrobe trunks are usually provided with locking means for the drawer section of the trunk, but the types of trunks which have an open top arrangement for the garment section, are generally unprovided with any locking means for safe guarding the garments against theft when the trunk is left open. It is a comparatively easy matter for an unauthorized person to remove a hanger with the garment supported thereby, from the trunk, when open, and one object of this invention is to provide locking means in connection with the pad or cushion, for preventing the hangers from being moved forward on their rails, or lifted therefrom thereby making it difficult for an unauthorized person to remove any garment from the trunk although the trunk is in open position.

The invention consists, therefore, in a wardrobe trunk of the "open top" type, provided with a movable pad or cushion, swingingly supported by the garment section of the trunk, and arranged to be swung down on the garment hangers in pressing engagement therewith and having a lock for locking the pad down on the hangers. It further consists in a lockable pad or cushion as above set forth, provided with an abutment or stop member at its front edge arranged to stand in front of the foremost garment hanger or follower, when the pad is locked down, and thereby prevent the hangers from being drawn forward or lifted from the rails or hanger bars which support them. It further consists in the several novel features herein-after fully set forth and claimed.

The invention is clearly illustrated in the accompanying drawing, in which:

Fig. 1 is a perspective view of an open top

wardrobe trunk equipped with a hanger retaining pad or cushion top device embodying a simple form of the present invention; Fig. 2 is a perspective view, looking from below, of the pad or cushion top device and a fragment of the garment section of the trunk, showing the two detached from each other; Fig. 3 is a detail vertical longitudinal section through the upper part of the garment section of the trunk, and Fig. 4 is a detail, vertical cross section taken through said garment section of the trunk.

Referring to said drawing which illustrates a typical form of the preferred embodiment of the invention, the reference character 5 designates the drawer section, and 6 the garment section of a wardrobe trunk of conventional form, the two sections being hinged together on a vertical line and provided with locking means for locking the sections together. The upper end or top of the wardrobe section is open, and is arranged to be closed by a trunk top, lid or cover 7, which in this case is shown as hinged to the garment section. The lid or cover is arranged to be locked down on the garment section whenever the two sections are locked together as is well understood. The trunk top 7, when open, affords ready access to the garment hangers 8, upon which the garments are draped, and which hangers rest on hanger bars or rails 9 that are rigidly mounted on the trunk walls at the open top of the garment section. In many cases a follower or presser board 10 is provided at the front of the hangers, which follower also rests on the hanger rails and is provided with some sort of latch mechanism for holding it in pressing engagement with the garments. The parts described are common and well known and require no further description as far as this specification is concerned.

In the form of the invention illustrated, an auxiliary top device 11 is provided between the tops of the garment hangers 8 and the underside of the trunk top 7, which device is swingably mounted on the garment section, whereby it may be raised or swung away from the garment hangers to afford ready access to them. The top device 11 is shown as hinged to an end wall 12 of the garment section, by a hinge 13 and its free end is provided with one member 14 of a lock, which co-operates with a companion lock member 15 fastened to the end wall 16 of the garment section. The lock may be of

the spring lock type, whereby when the auxiliary top device 11 is swung down on the garment hangers, the lock members 14, 15 co-act to lockingly hold the top device 11, 5 down upon the garment hangers. To prevent the hangers from shifting about, during transportation, the top device is provided with a pad or cushion 16, which is held in pressing engagement with the garment hangers whenever the top device is locked down thereon. In order to obtain strength and stability, the top device 11 may be formed with a rectangular frame 17 formed of metal, wood or the like, fitting fairly well 10 in the open top of the garment section. The pad or cushion 16 is filled with suitable cushioning material and is covered with fabric secured on or around the frame 17. When pressed down on the garment hangers the 15 pad prevents the hangers from shifting along their supports.

To further prevent the garment hangers from being drawn forward beyond the front edge of the auxiliary top device 11, a stop member 18 in the form of a lug or downwardly bent piece of metal is provided, which is secured to the front of the auxiliary top device, in position to stand in front of the foremost garment hanger or the follower 20 if the trunk is equipped with one. The stop member provides an abutment which arrests forward movement of the hangers beyond the auxiliary top device and prevents them from being lifted from their supporting bars 25 or rails when the auxiliary top device is locked down. In order that ready access may be had to the garments, the auxiliary top device is unlocked from the garment section of the trunk, and swung up and back 30 where it may assume the position illustrated in dotted lines in Fig. 1.

Among the especial advantages of this device, are its effectiveness in protecting the garments against pilfering while the trunk is open. It permits air to circulate about the garments, when the trunk is open whereby they may become thoroughly aired. It is simple, comparatively inexpensive, substantial and effective in operation.

More or less variation of the exact details of construction is possible without departing from the spirit of this invention, I desire, therefore, not to limit myself to the exact form of the construction shown and described, but intend, in the following claims, to point out all of the invention disclosed herein.

I claim as new and desire to secure by Letters Patent:

1. The combination with the garment section of an open top wardrobe trunk, its top, hanger rails and garment hangers, of a padded auxiliary top device for the open top of said section movable independently 60 of said trunk top, and co-operating lock

members, one on said garment section and one on the auxiliary top device, co-operating to lock the latter down upon the garment hangers in pressing engagement therewith, independently of the trunk top, whereby the 70 garment hangers are thereby held against movement relative to said auxiliary top device.

2. The combination with the garment section of an open top wardrobe trunk, its top, 75 hanger rails and garment hangers, of a swinging auxiliary top device for the open top of said section, having a pad arranged for engagement with said garment hangers and locking means on said garment section 80 and auxiliary top device for locking the latter down with the pad in pressing engagement with the garment hangers independently of the trunk top, whereby the garment hangers are thereby held against 85 movement relative to said auxiliary top device.

3. The combination with the garment section of an open top wardrobe trunk, its top, 90 hanger rails and garment hangers, of an auxiliary padded top device hingedly secured to a wall of said garment section, a lock member on said garment section and a lock member on said top device co-operating therewith to lock said device down with its 95 pad in pressing engagement with the garment hangers, independently of the trunk top, whereby the garment hangers are thereby held against movement relative to said auxiliary top device. 100

4. The combination with the garment section of an open top wardrobe trunk, its top, hanger rails and garment hangers, of an independently movable auxiliary top device for the open top of said section, a stop device secured at the front of said top device and arranged to stand in front of the garment hangers when the top device is in operative position, and co-operating lock members, one on said garment section and one on the auxiliary top device, co-operating to lock the latter down upon the garment hangers independently of the trunk top. 105

5. The combination with the garment section of an open top wardrobe trunk, its top, 110 hanger rails and garment hangers, of a swinging auxiliary top device for the open top of said section, and having a pad arranged for engagement with said garment hangers, a stop device secured at the front 115 of said top device and arranged to stand in front of the garment hangers when the top device is in operative position, and locking means on said garment section and auxiliary top device for locking the latter down with the pad in pressing engagement with the garment hangers independently of the trunk top. 120
